ABSTRACT: A simple sanitary napkin support belt is formed of elastomeric plastic film, and it is useful for supporting a menstrual napkin in a functional position on a female torso. A single waist belt can fit a majority of female torso sizes with no mechanical adjustment and the napkin support straps fit with minimum mechanical adjustment. The belt is sufficiently low cost to be discarded after using for one menstrual period.

SANITARY NAPKIN SUPPORT BELT

CROSS REFERENCES

This patent application is a continuation-in-part of my copending application Ser. No. 814,008 filed Apr. 4, 1969 teaching a sanitary belt, and also relates to my copending applications Ser. Nos. 720,500 and 742,922 teaching sanitary napkins. Further, this application relates to my U.S. Pat. application Ser. No. 720,502, for a sanitary belt.

BACKGROUND OF THE INVENTION

Sanitary belts partially made of rubberized elastic webbing have been conventionally used for decades, to support menstrual napkins in the functional position on the female torso. The waist belts are constructed with separate adjustable fasteners, so the belts are mechanically adjustable over a large range of torso sizes.

Before using the present commercial belt, each female must mechanically adjust the waist belt to her waist size. The belts are not extremely low in cost; hence, they are customarily bought separately from the napkins and reused by females for a large number of menstrual periods. For this reason, the female customarily keeps the napkin support belt in storage at home between menstrual periods, using it during her menstrual period.

Although menstrual napkins are widely sold at many types of retail stores and other outlets for quick demand, the lack of quick access to a sanitary napkin support belt at the required time can be very discomforting to the female. This invention teaches a very inexpensive sanitary belt which can be placed in each commercial retail package of sanitary napkins and sold as a part of the retail package.

SUMMARY OF THE INVENTION

On an endless, circular waist belt, two napkin support straps are slidably secured. The two support straps are mounted normal to the waist belt, when the belt is in the normal functional waist-hip position on a female torso.

The thin, highly elastic, plastic film waist belt is sealed into one piece. The waist belt plastic composition has a low tensile force after placement on the user's torso, due to a short stress relaxation time at the body temperature of 98.6°F.

The two narrow, thin, plastic napkin support straps can have higher tensile strength than the waist belt. Each thin support strap is double passed through at least two openings of a plural loop slide, the slide opening spacing adapted to confine each two layers of a support strap in a frictional brake compressive means. The relatively immovable return loop thereby formed by the two layers, supports a sanitary napkin at a slot opening taught in my copending application Ser. No. 742,922.

The sanitary napkin support belt can be formed of a plasticized polyvinyl chloride composition. The waist belt can be stretched to fit a wide range of female hip and waist contour sizes, utilizing only one manufactured nominal waist perimeter.

Included in the objects of this invention are:

First, to provide an inexpensive and compact menstrual napkin support belt having simple separate mechanical slide securing components for the napkin support straps.

Second, to provide a simple menstrual napkin support belt, which will fit a wide range of female torso sizes, with separate simple mechanical slide linkages or fasteners, operating in frictional brake compressive means.

Third, to provide a low cost sanitary belt which can be enclosed in a commercial retail package of menstrual napkins, to be used with the napkins in the package and then discarded.

Fourth, to provide low cost, easily manufactured sanitary napkin support belt made of components of elastomeric plastic film, the waist belt having a very low modulus of elasticity in tension and a short elongation recovery time.

Other objects and advantages of this invention are taught in the following description and claims.

BRIEF DESCRIPTION OF THE DRAWING

FIG. 1 is a perspective view of the improvement in a menstrual sanitary napkin support belt.

FIG. 2 is an enlarged plan view of the slit securing means disposed in each napkin support strap of the sanitary napkin support belt.

FIG. 3a is an enlarged elevational view of the adjustable return loop, frictional brake compressive strap securing means, useful for the sanitary napkin of U.S. application Ser. No. 742,922 or the like.

FIG. 3b is a sectional view through 3-3 of FIG. 3a illustrating further details of the frictional brake compressive securing means of this invention.

FIG. 4 is a plan view of another plural loop opening slide fastener which can be useful in forming an adjustable return loop, frictional brake, compressive strap securing means.

FIG. 5 is an elevational view of a female torso illustrating the application of the sanitary napkin support belt of this invention, in functional position, supporting a menstrual napkin taught by the copending patent applications Ser. Nos. 720,500 and 744,922.

DESCRIPTION OF THE PREFERRED EMBODIMENTS

Referring to FIG. 1 in detail, the sanitary napkin support belt 1 is shown in perspective view, having a highly elastic, plastic film, endless waist belt 2 and two narrow, thin, napkin support straps 3 and 4. The front napkin support strap 3 is typically shorter than the rear napkin support strap 4. The front strap 3 and the rear strap 4 are both mounted on the waist belt 2 at their respective first terminuses 5 and 6, by their respective single mounting slit openings 7 and 8. The waist belt 2 is typically sealed dielectrically at an overlap 9, to form an endless belt perimeter, after mounting the two straps 3 and 4 at the slit openings 7 and 8 respectively.

The two-loop slide fasteners 10 and 11 are shown in FIG. 1, slidably mounted on the narrow straps 3 and 4 respectively, each strap being threaded through both loops of the two-loop slides 10 and 11. Typically, the napkin support straps 3 and 4 are 13 in. and 22 in. long respectively, and both are typically $\frac{1}{2}$ in. wide by 0.012 in. thick.

The single slit opening 7 of the first terminus 5 of the napkin support strap 3 is shown in FIG. 2. The strap 3 is illustrated mounted on the flat waist belt 2. The single slit opening 7 adapts the strap 3 to be easily turned over if necessary, to place the required obverse face of the strap 3 in the needed direction when in use on a torso. The single slit opening 7 is also easy to automatically thread on a waist belt 2 progenitor, prior to automatically sealing the belt into an endless belt 2.

The belt 2 is illustrated as flat and rectangular in cross section; however, the belt can be circular or elliptical or square and other typical cross sections. Hence, the slit opening 7, and the like, can be correspondingly circular, elliptical, square or the like in shape, as fully equivalent to the slit opening 7. Typically the waist belt can be $\frac{1}{8}$ in. diameter, $0.01 \times \frac{1}{2}$ in., $0.013 \times \frac{1}{4}$ in. or the like in cross section, as required.

The details of the adjustable return loop, frictional brake, compressive strap securing means are shown in FIGS. 3a and 3b. The perspective view of FIG. 3a illustrates an adjustable length napkin support loop 30, threaded through the napkin slot 31, of the napkin 32, which is taught in U.S. application Ser. No. 742,922. The strap 3 is shown return threaded twice through the two loop slide fastener 10, the second strap terminus 12 being threaded through the fastener 10 after passing through the napkin slot 31, to form the return loop 30. Thus, the tensile loaded return loop length 33 in use can be adjusted in length as required, by adjusting the length of strap 3 which secured in the length 33.

Further details of the frictional brake function of the napkin strap securing means are shown in the enlarged sectional view FIG. 3b, taken through 3-3 of FIG. 3a. The two loop slide fastener 10 has a pair of slot openings 34 and 35, which are bounded by the slide bars 36, 37 and 38. The plastic strap 3 is shown double threaded through the slide 10 cross section,

placing the plastic strap 3 in compression over the width 39 of the slide 10. When the tensile loaded strap 3 is loaded in the tension force direction indicated by arrow 40 in FIG. 3a, the two portion lengths of the strap 3 which pass through the slot openings 34 and 35 are compressively secured against their respective contiguous faces of the slide bars 36, 37, and 38, as indicated by the compressive force arrows 41, 42, and 43 respectively. The compressive yielding of the soft plastic straps 3 and 4, typically having a Durometer Shore A hardness of 60-80 or the like, produces a strong nonslip braking force on the napkin support straps 3 and 4, or the like. Thus the compressed portions of strap 3, pushing against slide bars 36, 37 and 38, form a type of frictional brake system, somewhat similar to a standard vehicle frictional brake. The coefficient of friction of the slide bars 36, 37 and 38 can be further amplified by coating the slide fastener 10 with a low compressive strength polyvinyl chloride plastisol, by known technique. The thin PVC coating 44 on the metal slide base can further increase the friction coefficient between the slide fastener 10 and the adjacent portions of the strap 3. The compressive, frictional brake securing means of strap 4 and fastener 11 is fully equivalent to that of strap 3 and fastener 10.

A further slide fastener 50 modification is shown in plan view in FIG. 4, wherein the fastener has three slot openings 51, 52, 53 and the four slide bars 54, 55, 56, 57. The slide bars 54-57 can be rough surfaced, to further increase the coefficient of friction in the frictional brake means. The slide fastener 50 can be cheaply molded of plastic.

Typically the napkin support straps, 3 and 4 and the like, can range in thickness from 0.008 to 0.020 in., and can be the width required to support the napkin 32 at the slot 31, or the like. The surface smoothness of the straps 3 and 4, or the like, can range from a polished glass smoothness to a roughness corresponding to an embossed simulated linen weave, or the like.

The low density polyethylene has a sufficiently low durometer hardness to deform under tension and form a frictional brake binding strap loop 30, or the like. However, the polyethylene tends to cold stretch and it is more rigid compared to a properly plasticized polyvinyl chloride film composition, and also has a harsher feel to the body. Typically a plasticized polyvinyl chloride film containing 38 to 44 percent dioctyl phthalate as plasticizer is sufficiently elastic, soft to the skin, and deformable, to function in the frictional brake, napkin support strap securing means. The plasticized film should not contain toxic stabilizers and the like, which could irritate the skin. Further, by prior cold stretching of the film napkin support straps, one can effectively utilize the elastic memory of plasticized polyvinyl chloride. The elastic memory of the film will tend to contract the strap on use at body temperature, tending to keep a napkin tightly positioned against the vaginal opening.

FIG. 5 illustrates the functioning of the menstrual sanitary napkin support belt 1 of this invention. The belt 1 is shown in normal functional position on the female torso 60. The waist belt 2 encircles the torso 60 in a region between the waist and hip. Due to the elasticity of the waist belt 2 and its short stress relaxation time the belt 2 can be stretched from its typical normal manufactured perimeter of 26 in. to 40 in. or more. Typically the single waist belt perimeter of 26 in. can fit females, wearing dress size regular 7 to dress size regular 36. The above range of dress sizes correspond to a waist of 22½ in. and hip of 32 in. for dress size regular 7, to a waist of 31 in. and hip of 40 in. for dress size regular 36, according to the U.S. Department of Commerce Report CS 215-58, 215-58.

After functional placement of the waist belt 2, the rear napkin support strap 4 can be slid to the front of the torso and the menstrual sanitary napkin 32' threaded through a napkin slot and looped upward to form a long return loop secured by the slide fastener 11, as illustrated in FIG. 3a, or the like. It should be noted that the slide fastener 11 is positioned up near the waist or hip position of the waist belt 2 perimeter, in order to place the fastener 11 in a position where it will lie flat against

the female back, not in the crotch. After returning strap 11 to the rear, the napkin 32' is centered in place, over the vaginal opening and the front napkin support strap 3 threaded through the front napkin slot 31' of FIG. 5, and then formed into a short return loop 30' secured by the slide fastener 10, as in FIG. 3a, or the like, pulling the napkin into a tight confronting position, to receive the discharged menstrual fluid from the vaginal opening.

Since the loops are infinitely adjustable in length, the napkin can thus be secured in front of the vaginal opening with the desired degree of napkin tightness, to receive fluid. Napkin tightness is a most important parameter in the social security of the female using the sanitary napkin, in order to positively receive all menstrual fluid discharge on the napkin.

15 The specific properties of suitable polyvinyl chloride compositions containing 38-43 percent equivalent of DOP ester plasticizer is listed below in Table I.

TABLE I

20	Stiffness (D1043)* at 23° C., ave. p.s.i.	650-1,400
	Tensile strength (D882) transverse direction, min. p.s.i.	1,800-2,500
	Ultimate elongation (D882) transverse direction, min. percent	180-300
	Brittle temperature (D746) 50% non-failure, ° C.	-12-46
	Durometer hardness (D676) Shore type A, 15 sec. reading, ave.	61-77

* The numbers are ASTM test procedures.

The plastic compositions having these properties are particularly soft in feel, and elastic enough to form the waist belt and support strap of this invention. From the viewpoint of the users torso comfort it is very important that the above-described compositions have a short stress relaxation time at body temperature (98.6° F.). Thus, the stretched plastic waist belt rapidly assumes a low tensile force after placement on a user's torso. The plastic softness greatly reduces the chafing potential of the napkin support strap in use.

Other plastic compositions which can comply with the above type range of physical properties can be used. The plastic composition must be nontoxic. This invention is not specifically limited to polyvinyl chloride plasticized film compositions.

This inventive advance in sanitary support belts functionally provides very effective heat transfer from the female torso to the closely confronting sanitary napkin worn adjacent the vaginal opening. Hence, the body heat functions very effectively to rapidly evaporate the approximately 95 percent moisture from the menstrual fluid absorbed on the napkin. The present conventional commercial sanitary napkins, in combination with the conventional support belt, are not effective in holding the napkin in a position to effectively raise the heat transfer rate to a commercial absorbent pad. In addition, the commercial napkin is a very effective heat insulator, not a good heat transfer path means. Hence, the combination of the napkins disclosed in Ser. Nos. 720,500 and 742,922 and the sanitary belt of this invention represents an important inventive advance in the art.

Other waist strap and napkin support strap geometrical variations in dimensions can be made without departing from the scope of this invention. Many modifications and variations 60 of my improvements in this sanitary napkin support belt can be made in light of my teachings. It is therefore understood that within the scope of the appended claims, the invention may be practiced otherwise than as specifically described.

I claim:

- 65 1. A sanitary napkin support belt comprising:
  - a. an elastomeric plastic, endless waist belt, having an unstressed perimeter elastically adapted to snugly fit at least minimum female torso dimensions, said plastic belt having low tensile force and short stress relaxation time at human body temperature;
  - b. two narrow, thin, elastomeric plastic, napkin support straps, each said strap slidably mounted on said waist belt through an opening in a first strap terminus; and
  - c. a pair of plural adjustable loop, compressive frictional
- 70 75 strap securing means, one strap securing means

disposed on each napkin support strap, each strap securing means comprising a plural loop slide and a second strap terminus flat length tightly, twice threaded through each one of the loop openings of the plural loop slide, to form a napkin support strap return loop, both of the return loop straps compressively, frictionally adhered to said plural loop slide.

2. A sanitary napkin support belt of claim 1 in which each said napkin support strap is slidably mounted on a single opening in said first strap terminus.

5

3. A sanitary napkin support belt of claim 1 in which said plastic waist belt and plastic napkin support straps have the elastomeric physical properties described within the ranges of Table I.

4. A sanitary napkin support belt of claim 3 in which the plastic waist belt and the plastic napkin support straps are plasticized polyvinyl chloride compositions.

5. The sanitary napkin support belt of claim 1 in which the plural loop slides each have two loop openings.
